UNITED STATES PATENT OFFICE.

ALPHEUS FOX, OF ROCK FALLS, ILLINOIS.

CORN-PLANTER.

SPECIFICATION forming part of Letters Patent No. 274,928, dated April 3rd, 1883.

Application filed November 11, 1882. (No model.)

To all whom it may concern:

Be it known that I, ALPHEUS FOX, a citizen of the United States, residing at Rock Falls, in the county of Whiteside and State of Illinois, have invented certain new and useful Improvements in Corn-Planters; and I do hereby declare the following to be a full, clear, and exact description of the invention, such as will enable others skilled in the art to which it applies to make and use the same, reference being had to the accompanying drawings, and to letters or figures of reference marked thereon, which form a part of this specification.

My invention belongs to that class of corn-planters in which two rows are planted at one time and the hills are deposited in cross-rows or checks; and my invention has more especial reference, first, to certain improvements in the dropping mechanism, and, second, to devices for raising or forcing down the front frame and locking the front and rear frames in certain relative positions to regulate the depth of planting.

In the drawings, Figure 1 is a plan view of a machine embodying my invention. Fig. 2 is a detached view of the plates constituting the dropping mechanism. Fig. 3 is a detached view of the devices for raising, lowering, and locking the front frame on the rear frame.

30 A is the ordinary front frame of a two-horse corn-planter. B is the rear frame. The front frame is carried on the furrow openers or runners A' A', and the rear frame on the carrying and covering wheels B' B'.

35 C is the usual reciprocating bar operated by the hand-lever D, or in the usual way by an automatic check-rower.

E is a circular plate, provided on its upper surface with a circular series of five short vertical equidistant studs a.

40 A slot, w, is formed in the bar C, through which the upper end of the vertical axle c of the plate E passes, the purpose of such slot being to permit the reciprocal action of the bar C.

45 On the lower surface of that part of the bar C which plays over the plate E are affixed two cams, b' b', of the form of an isosceles triangle or a half-diamond. The outer cam, b', is placed near the end of the bar C, with its point or apex inward, and the other cam, b', is placed

with its apex outward at a distance inward from the first cam b' of a little less than the diameter O of the plate E. The purpose of the cams b' is to give a revolving motion to the plate E by engaging alternately the studs a thereon. The studs a are placed at such intervals, and the cams b' are of such size and shape, as that when the point of each cam b' is moved by the bar C from the periphery of the plate E toward the center of the latter, such point will strike one side of one of the studs a, and the inner movement of the cam force the stud a to one side, thus partially rotating the plate E. The stud a next succeeding the one thus struck strikes against the opposite side of the cam b' at the limit of the inner stroke of the latter, thus affording a stop. When the bar C is moved in the opposite direction, the other cam, b', repeats the operation just described. Of course one pair of cams b' are placed at each end of the bar C.

The vertical axle c of the plate is journaled at its lower end in the beam F, and at its upper end in the plate G, which constitutes the bottom of the seed-box. The plate G has the hole d for the passage of the seed, such hole falling outside of the plate E, so that the seed can drop past the latter into the vertical seed-tube H.

50 K is the rotating seed-plate, provided with the annular series of seed-cups e, such seed-cups being double in number of the studs a on the plate E. The plate K has a square hole in its center, which fits over the upper end of the axle c of the plate E, such axle being shaped to conform to such hole and causing the plate K to rotate synchronically with the plate E. At each intermittent rotation of the plate K the seed-cups e successively register with the hole d in the plate G, so as to discharge the seed.

55 L is a cut-off plate, placed over the seed-plate K, and provided with the annular slot M above the series of seed-cups e, which directs the grain into such cups and insures their filling. The slot M is crossed at different intervals by the several cut-offs f, which assist in uniformly filling the seed-cups e by adjusting the kernels of corn therein.

60 The tube H has a pivoted back, g, which is suitably connected at the top to the bar C and

oscillated transversely thereby. There is a vertical partition, h_1 , at the center of the inside of the back g , making two vertical channels in the tube H , with the ordinary shelf at the bottom. I remove the upper part of the back g , leaving the hole i , through which the descending corn can be seen by the operator.

The mechanism employed to regulate the altitude of the front frame is as follows: The frames A and B are hinged together at their point of junction in any suitable way. A bar, N, fastened under the center of the frame A, extends nearly or quite in a line with the tongue back under the center of the frame B. To the rear end of the bar N is attached a cord or chain, k , which passes up and over a pulley, l , set transversely of the machine on the front side of the standard m of the driver's seat P, and is attached to the lever R on the opposite side of such standard. The lever R is hinged at its front end to the front cross-beam of the frame B, and the rear ends of both the bar N and lever R are provided with suitable rests for the driver's feet, and placed convenient for the driver to rest one foot on each. It is obvious that when the rear end of the bar N is pressed down it will have the effect of forcing the runners A' of the front frame into the ground, and at the same time, through the medium of the cord k , raise the rear end of the lever R. By forcing the lever R downward a contrary result will be obtained, and the runners lifted out of and above the ground, as may be desired. On the bar N, and in close proximity to the cross-beam S, on which the seat-standard m is seated, is placed a vertical standard, T, having a series of notches, n , on its side. A short horizontally-oscillating lever, v , is pivoted on the top of the beam S, in such position that its inner end may be forced in or out of the notches n at the will of the driver. By this means the frames A and B may be held at any relative height, and the front frame be held clear off

the ground in turning around or going to and from the field.

What I claim as my invention, and desire to secure by Letters Patent of the United States, is—

1. The reciprocating bar C, having the slot w and cams b' , in combination with the rotating plate E, provided on its upper surface with the annular series of studs a , substantially as shown, and for the purpose described. 50

2. The bar N, cord k , standard m , provided with the pulley l , and lever R, in combination, substantially as shown, and for the purpose described. 55

3. The bar N, attached to the front frame, A, the lever R, fulcrumed to the rear frame, B, and such bar and lever connected by a cord or chain, k , whereby the downward movement of the bar produces a contrary movement of the lever, and vice versa, and the relative altitudes of the frames A and B are changed 60 and regulated, substantially as shown, and for the purpose herein named. 65

4. The bar N, affixed to the front frame, A, the lever R, fulcrumed to the rear frame, B, the standard m , having the pulley l , the cord k , the standard T, having the notches n , and the lever v , in combination, substantially as shown, and for the purpose specified. 70

5. The front frame, A, having the bar N, and standard T, having the notches n , and the rear frame, B, having the lever v , in combination, substantially as shown, and for the purpose mentioned. 75

6. The tube H, having at its upper end the hole i , through which the descending corn can be seen, substantially as shown, and for the purpose specified. 80

In testimony whereof I affix my signature in presence of two witnesses.

ALPHEUS FOX.
